(57) **CLAIM**

The ornamental design for a livestock head covering, as shown and described.

DESCRIPTION

FIG. 1 is a front, left perspective view of a livestock head covering comprising the new design;

FIG. 2 is a front elevational view of the design of FIG. 1; FIG. 3 is a back elevational view of the design of FIG. 1; FIG. 4 is a right elevational view of the design of FIG. 1; FIG. 5 is a left elevational view of the design of FIG. 1; FIG. 6 is a top view of the design of FIG. 1; and, FIG. 7 is a bottom view of the design of FIG. 1.

The broken lines shown in the figures are directed to the environment and are for illustrative purposes only; the broken lines form no part of the claimed livestock head covering invention.

1 Claim, 4 Drawing Sheets
